REFLECTION SIGN

Reuben H. Noble, Selma, Calif., assignor of forty-five per cent to W. J. Jackson, Kingsburg, Calif.

Application May 16, 1933. Serial No. 671,390

7 Claims. (Cl. 40—130)

This invention relates to improvements in signs and pertains particularly to an improved form of electric reflection sign.

The primary object of the present invention is to provide an improved reflection sign of novel construction and wherein the adjustment of the reflectors may be readily made for the purpose of varying the angle of reflection.

Another object of the invention is to provide an electric reflection sign having novel means for retaining in readily movable position the transparent or translucent or stenciled bodies which carry the matter to be reflected from the mirrors of the structure.

Still another object of the invention is to provide an improved reflection sign having a novel light housing which in addition to serving as a protection for the lighting means covers and protects the mirrors and the bodies through which the light is transmitted onto the mirrors.

A still further object of the invention is to provide a novel type of electric reflection sign having novel means for removably supporting the advertising matter carrying plates or stencils so that the same may be easily and quickly removed when it is desired to change the character of the matter on display.

The invention will be best understood from a consideration of the following detailed description taken in connection with the accompanying drawings forming part of this specification, with the understanding, however, that the invention is not confined to any strict conformity with the showing of the drawings but may be changed or modified so long as such changes or modifications mark no material departure from the salient features of the invention as expressed in the appended claims.

In the drawings:—

Figure 1 is a view in side elevation of the sign structure embodying the present invention, a portion of the top of which is broken away;

Figure 2 is an end elevation of the structure;

Figure 3 is a transverse sectional view taken upon an enlarged scale on line 3—3 of Figure 1;

Figure 4 is a detail section taken upon the line 4—4 of Figure 3;

Figure 5 is a detail of the central portion of one end illustrating the means for removing the advertising plates.

Referring now more particularly to the drawings wherein like numerals of reference indicate corresponding parts throughout the several views, it will be seen that the present structure comprises two vertical end bars or standards,

each of which is indicated by the numeral 1, between the upper ends of which is secured a T-beam 2 in which the web portion is directed downwardly. Intermediate the ends of the vertical members 1 is a second T-beam which is indicated by the numeral 3 and which has the web directed upwardly so that the head serves as a supporting means in the manner hereinafter described and the web portion operates as a partition or separating means between the supported articles.

Extending transversely of the vertical standards 1 and across the adjacent ends of the intermediate T-beam 3 are the horizontal T-beams 4. These transverse T-beams 4 have their outer ends connected by the channel irons or U-beams 5, the channels of which are directed inwardly toward the center T-beam 3 as shown, and the lower flange of each channel iron is in the same plane as the head of the T-beam 3.

The vertical standards 1 are each provided with the longitudinal slot 6 and slidably engaged in each of these slots is a pin 7 which pivotally couples together the overlapped ends of a pair of link members 8. These links extend in opposite directions from the adjacent standards 1.

Upon each side of the center of the structure beneath the plane of the beams 3 and 4 is a channel iron frame 9 in which is mounted a mirror 10 which may be of polished metal or glass, as desired. Each of these mirror frames 9 is pivotally mounted upon and between the standards 1 directly beneath the T-iron 3 and adjacent the longitudinal edge opposite the longitudinal edge which is disposed beneath the beam 3 each mirror frame is pivotally attached at each end to a free end of a link 8. It will thus be seen that the links 8 at the ends of the side structure serve to retain the lower edges of the mirrors in position upon the underlying supporting structure 95 and it will also be apparent that by sliding the link connecting pins 7 upwardly in the slot 6 the lower edges of the mirrors may be swung inwardly to change the angle of reflection.

At each end of the sign structure above the beams 4 a vertical end wall 11 is secured to the adjacent upright 1. These end walls have their top edges inclined from the beam 2 toward the outer ends of the beams 4 and connecting these inclined edges and also connecting the beam 2 with the U-beams 5 is a hood or top wall 12, the longitudinal edges of which are suitably detachably secured as indicated at 13 to the beams 2 and 5 so that the walls may be readily removed 110

from the beams when it is necessary to reach the interior of the side structure.

Slidably engaged in each of the channel irons 5 are the edges of glass panels 14, the opposite edges of which rest upon the adjacent flange of the center T-beam 3. These glass panels may be of clear or colored glass as desired and may have overlying them a stencil plate 15 in which figures or characters are formed which are to be outlined upon the underlying mirror 10 for reflection therefrom. It will, of course, be readily apparent that instead of using a glass panel and a stencil plate there may be used simply a glass plate which has the figures or characters blocked out or which has been etched or painted to outline the same in any suitable manner to obtain their reflection from the underlying mirrors.

Since the character carrying bodies such as the glass panel or the stencil plate are slidably disposed between the channel irons or bars 5 and the bar 3, it is apparent that one of the end walls must be formed in a suitable manner to facilitate their being changed and while any suitable means may be employed which will facilitate the ready changing of the character carrying panels and which at the same time will protect the same when the sign is in use, there has been illustrated a door 16 cut from one end wall 11 and hingedly attached thereto, as indicated at 17, so that upon being swung to open position the elements 14-15 may be readily withdrawn. The adjacent standard 1 will, of course, be suitably recessed to permit these units to be withdrawn.

Housed within the housing formed by the roof or hood 12, the end walls 11 and the units 14 and 15, are longitudinally extending downwardly directed reflectors 18, each of which overlies a glass panel and stencil 14-15. These reflectors may be supported in any suitable manner and extending into the same are the electric wire conduits 19 which lead to electric light sockets 20 in which are placed suitable illuminating elements 21 which are preferably in the form of elongated or cylinder shaped electric bulbs of the character commonly employed in show-cases.

From the foregoing it will be readily apparent that with the structure herein described the display of any advertising or other matter may be made without exposing the essential elements of the structure to the weather and it will also be apparent that changes may be easily and quickly made in the advertising units which comprise the plates 14 and 15 or which may comprise simply a suitably outlined or blocked out sheet of glass, as previously described. In addition, the maximum of advertising efficiency may be obtained as a result of the means provided for adjusting the angle of the reflectors or mirrors 10 which in addition to serving as a means for transmitting advertising matter contained upon the illuminated units, operate as a supporting base for the structure.

Having thus described the invention, what is claimed is:—

1. An advertising structure, comprising a pair of standards, a beam connected between the standards, a beam extending laterally from each standard in the same plane as the first beam, a channel beam connecting the outer ends of the lateral beams, a character bearing light transmitting element horizontally supported between the first mentioned beam and the channel beam, means forming a chamber over said light transmitting element, a light fixture within the chamber, and a mirror disposed at an inclination be-

neath the light transmitting element and secured between said standards.

2. An advertising structure, comprising a pair of standards, a beam connected between the standards, a beam extending laterally from each standard in the same plane as the first beam, a channel beam connecting the outer ends of the lateral beams, a character bearing light transmitting element horizontally supported between the first mentioned beam and the channel beam, means forming a chamber over said light transmitting element, a light fixture within the chamber, a mirror disposed at an inclination beneath the light transmitting element and secured between said standards, said mirror being pivotally connected with the standards, and links pivotally connecting the lower edge of the mirror with the standards whereby the angle of the mirror with respect to the light transmitting element may be changed.

3. An advertising structure, comprising a pair of spaced upright bodies, a pair of spaced parallel beams each secured to and extending across one of said bodies, a T beam connected between said bodies and having its web directed upwardly, channel beams connecting the outer ends of the parallel beams and having the channels thereof directed inwardly toward the T beam, character bearing light transmitting bodies each having one edge slidably disposed in a channel beam and its opposite edge slidably supported upon the T beam in opposition to the web thereof, cover means overlying the light transmitting bodies, an illuminating element above each of the light transmitting bodies, and a reflector disposed at an inclination to and beneath each of the light transmitting bodies.

4. An advertising structure, comprising a pair of standards each having a vertical slot, a pair of horizontally disposed light transmitting character bearing bodies carried by and between said standards, means for illuminating the light transmitting bodies from the top thereof, a pair of mirrors each disposed beneath a light transmitting body and at an angle thereto, each of said mirrors being pivotally connected at its ends with the adjacent standards, a pair of links at the lower part of and extending laterally from each standard and having their ends in overlapping relation, a pin pivotally coupling the overlapped ends of the links and slidably engaging in the adjacent standard slot, and a pivotal connection between each of the mirrors adjacent the lower edge of the same and a pair of link members.

5. A sign structure of the character described, comprising a pair of vertically disposed standards, a T beam connecting said standards at their upper ends, a T beam connecting the standards intermediate their ends and having its web directed upwardly, a beam extending transversely of each standard adjacent the second T beam, a channel beam connecting the outer ends of the transverse beams and having its channel directed inwardly, vertical walls carried by said standards and having their lower edges adjacent the transverse beams, top walls overlying the top edges of the end walls and connected between the first T beam and a channel beam, character bearing light transmitting plates each having one edge slidably disposed in a channel beam and having its opposite edge slidably mounted upon the second mentioned T beam in opposition to the web thereof, lighting units overlying each of said light transmitting bodies, reflector elements each oscil-

latably mounted between the standards beneath and at an angle to the light transmitting bodies, and means coupling the lower edges of the reflector units with the standards whereby the units 5 may be angularly adjusted.

6. A sign structure of the character described, comprising a horizontal light transmitting character bearing body, vertical supporting standards arranged in spaced parallel relation beneath 10 and adjacent opposite sides of said body for supporting the same, a mirror disposed beneath said body and between said supporting standards, pivotal connecting means between the mirror and the standards, at a point on the standards adjacent 15 the said body, link elements at opposite sides of said mirror and each pivotally connected at one end therewith adjacent the lower edge thereof, and means connecting the other end of each link element with an adjacent standard whereby 20 said other end may be adjustably secured to and longitudinally along the standard, the said light transmitting character bearing body being designed to have light projected therethrough

downwardly toward said mirror whereby the characters thereon will be reflected from the mirror.

7. A structure of the character described, comprising a housing having a top and end walls, a door opening formed transversely of one end wall adjacent the lower edge thereof, a pair of supporting beams extending longitudinally of the housing between the end walls, a light transmitting character bearing body slidably extended through said door opening into the housing and slidably supported upon said beams, a door member normally closing said opening, standards supporting said housing, a mirror pivotally suspended between said standards to position beneath said light transmitting body, lighting elements in the housing above said body and connecting means between the mirror and the standards whereby the angular adjustment of the mirror relative to the light transmitting body may be effected, said light transmitting body constituting the bottom wall of the housing.
